UNITED STATES PATENT OFFICE.

WILLIAM A. PETERSON, OF CHARLOTTE, NORTH CAROLINA.

OPERATING MECHANISM FOR TRACTORS.

1,316,922.

Specification of Letters Patent. Patented Sept. 23, 1919.

Application filed March 14, 1918. Serial No. 222,468.

To all whom it may concern:

Be it known that I, WILLIAM A. PETERSON, citizen of the United States, residing at Charlotte, in the county of Mecklenburg and State of North Carolina, have invented certain new and useful Improvements in Operating Mechanism for Tractors, of which the following is a specification.

This invention relates to tractor engines, and more particularly to a tractor especially adapted to be used in connection with agricultural operations.

One of the main objects of the invention is to provide a tractor which is of comparatively simple construction and operation which is capable of developing comparatively great power. A further object is to provide a tractor, the bull-wheel shaft of which is rotated by means of lever rods or shafts thereto, these shafts being of relatively great length and being reciprocated by means rotated by an internal combustion engine mounted on the tractor frame, the shafts because of their relatively great length rendering it possible to develop relatively great power from a small initial power. A further object is to provide speed changing means whereby the throw of the lever-shafts may be accurately adjusted within comparatively wide limits thus permitting accurate and minute adjustment of the speed. Another object is to provide simple and efficient gearing and shifting means therefor, whereby the direction of rotation of the bull wheel shaft may be further readily reversed so as to reverse the direction of travel of the tractor. A further object is to provide simple and efficient clutch mechanisms whereby the operation of the drive gearing may be readily controlled, and the bull wheels may be optionally connected to the bull-wheel shaft for rotation therewith. Further objects will appear from the detailed description.

45 In the drawings:

Figure 1 is a top plan view of a tractor constructed in accordance with my invention, the hood for the drive gearing and the hood for the lever shaft operating mechanism being both partly broken away,

Fig. 2 is a side view,

Fig. 3 is an enlarged top plan view of the drive shaft and disks showing the speed changing mechanism and associated parts, also showing the main clutch and gearing in section.

Fig. 4 is a fragmentary horizontal section through the drive gearing and the bull-wheel clutches, and associated parts,

Fig. 5 is an inside or back view of the gear changing mechanism for the drive gears, and associated parts, the tractor frame being shown in section,

Fig. 6 is a top plan view of the gear changing rods and associated parts, 65

Fig. 7 is a vertical section taken substantially on line 7—7 of Fig. 4,

Fig. 8 is a vertical section taken substantially on line 8—8 of Fig. 4, partly broken away, 70

Fig. 9 is a section taken substantially on line 9—9 of Fig. 4,

Fig. 10 is a section taken on line 10—10 of Fig. 4,

Fig. 11 is a section taken on line 11—11 75 of Fig. 4,

Fig. 12 is a section taken on line 12—12 of Fig. 3,

Fig. 13 is a section taken on line 13—13 of Fig. 3, 80

Fig. 14 is a side view of the gear changing control mechanism and associated parts,

Fig. 15 is a top plan view of the same,

Fig. 16 is a section taken on line 16—16 85 of Fig. 14,

Fig. 17 is a section taken on line 17—17 of Fig. 15,

Figs. 18 to 21 inclusive are semi-diagrammatic views of the driving disks showing the four relative positions of the crank shafts 90 and associated parts,

Fig. 22 is a top plan view of the levers and racks for operating the bull-wheel clutches, and the gear shifting and speed changing mechanism, 95

Fig. 23 is a side view of the same,

Fig. 24 is a section taken substantially on line 24—24 of Fig. 23,

Fig. 25 is a detail of the means for locking the adjusting screw of one of the drive 100 disks against rotation,

Fig. 26 is a section taken substantially on line 26—26 of Fig. 1, showing the steering gear,

Fig. 27 is a section taken on line 27—27 105 of Fig. 1,

Fig. 28 is a detail of the attaching hook.

The main frame of the tractor is of I-beam construction having the side beams 1 and 2, front end beam 3, and the back end beams 4 110 which converge rearwardly to produce a substantially V-shape frame rigidly secured

to the body of the main frame. A cross beam 5 is secured in the main frame adjacent the forward ends of end beams 4. This cross beam supports a bearing block 6 in 5 which is rotatably mounted a steering standard 7 provided at its upper end with a steering wheel 8. This shaft is so positioned as to permit the wheel, to be readily grasped by a person seated in the seat 9 supported by bars 10 secured to cross beam 5 and a cross bar 11 which is secured to the end bars 4 a short distance from the apex of the V outlined by these bars. A steering chain 12 is wrapped about standard 7 intermediate collar 13 secured thereon and a pinion 14 secured on the standard adjacent the upper face of cross beam 5. The ends of this chain are secured to the opposite ends of a steering beam 15 which is secured on 15 the upper end of the stem 16 of a fork 17 in which is rotatably mounted the steering wheel 18. Stem 17 of the fork projects through a block 19 which is secured between I-bars 20 secured to cross bar 11 and to end beams 4, bars 20 being equidistant from the center of the frame. A locking lever 21 is rockably mounted in a supporting bracket 22 secured on cross beam 5 and center beam 23. This lever is provided with a forwardly 25 projecting finger 24 which is adapted to engage the teeth of pinion 14 so as to secure this pinion against rotary movement. By this means, the steering standard 17 is locked against rotation thus locking the 30 chain 12 against movement so as to secure the steering wheel 18 in adjustment. The wheel 18 may be readily turned by means of standard 7 and hand wheel 8 when the lever 21 is moved into inoperative position, thus 35 providing simple and efficient means for steering the tractor. To permit ground working implements, or vehicles to be readily attached to the tractor, I provide an attaching hook 25 which is mounted on a securing bolt 26 provided at each end with a 40 plate 27 which may be secured to the flanges of the I-beams 4. This hook is positioned at the apex of the V formed by the frame beams 4, which is at the transverse center 45 of the tractor. This enables implements or vehicles to be readily secured to the tractor, the rearwardly converging beams permitting slight necessary movement or play of an implement or vehicle thus secured. 50 For operating the tractor, an internal combustion engine designated generally by A is mounted on the tractor frame in advance of the operator's seat 9. This engine may be of any suitable or standard construction, and of any type desired. The crank shaft 28 of the engine is extended and is braced and supported by bearing blocks 29 secured on the side bars of the tractor frame through which this shaft projects. A gear 65 wheel 30 is secured on one end of shaft 28 and meshes with a gear wheel 31 which is loosely mounted on a stub shaft 32 rotatably supported by a bearing block 33 secured on side beam 2 of the main frame. Wheel 31 is provided, in its outer face, with a substantially frusto-conical recess 34 which is adapted to receive a clutch disk 35 provided with a clutch band or rim 36 made of wood or other suitable material which will grip tightly frictionally the inner surface of the rim of gear 31, the outer periphery of rim 36 being beveled inwardly for this purpose. A cover or cap 37 is secured to the outer end of hub 38 of disk 35 so as to rotate therewith. Cap 37 is provided with a central opening through its outer end which receives the body portion of a disk 39 provided at its inner end with an outer annular flange 40 which co-operates with a securing plate 41 secured to the outer end of the disk 45 adjacent the outer face of the outer end of cap 37 to secure disk 39 in the cap so as to be freely rotatable therein while positively preventing movement of disk 39 longitudinally of the cap. Disk 39 is centrally bored 50 and threaded to receive a threaded adjusting screw 42 the inner end of which is secured by loose nut connections to the outer end of stub shaft 32 so as to permit independent rotation of the shaft. The outer end of screw 42 is secured to the lower end of an arm 43 the upper end of which is connected by a rod 44 to the upper end of an arm 45 secured on the shaft 46 of a hand lever 47 which is rockably supported by a segmental 55 rack 48 secured to side bar 2 of the frame, this hand lever being provided with a spring pressed detent which co-operates with rack 48 to secure the lever in adjustment, in the usual manner. By rocking lever 47 downwardly and forwardly the screw 42 will be rotated in such direction as to force disk 35 inwardly so as to bring the friction rim or band 36 into tight frictional engagement with the inner surface of the rim of gear 60 31. By this means, rotation of gear 31 will be imparted to the disk 35. As will be noted more particularly from Fig. 3, the outer end portion 32a of shaft 32 is squared and fits into a corresponding bore in hub 38 65 of disk 35 so that rotation of this disk will be imparted to the shaft. By means of the hand lever 47 and the associated parts, shaft 32 may thus be readily connected to or disconnected from, the crank shaft 28 of the 70 engine A.

Stub shaft 32 is in axial alignment with a plurality of stub shafts 49 which are rotatably supported in bearing blocks 50 secured on the beams 51 secured to the cross beam 52 of the main frame and to the cross beam 53 which co-operates with beam 54 to support the engine. Stub shafts 49 are in axial alignment with a stub shaft 55 rotatably supported by a bearing block 56 secured on 75

120

125

130

side beam 1 of the main frame. Drive disks 57 are secured on the stub shafts 32, 49 and 55. These disks are disposed in axial alignment and are arranged in pairs between the 5 beams 51, and the outermost beams 51 and side beams 1 and 2 of the main frame. Each pair of disks 57 supports a crank shaft 58 which extends between the disks. This crank shaft is provided at each end, as will 10 be noted more clearly from Figs. 18 to 21 of the drawings, with a squared block 59 which is slidable in a substantially rectangular slot 60 through the disk and extending radially thereof. It will be understood, of 15 course, that the slots 60 in each pair of disks are in alignment transversely of the main frame of the tractor. An adjusting screw 61 is threaded through block 59 and has its outward movement positively pre- 20 vented by a collar 62 secured on the stem of the screw and in engagement with the outer end wall of slot 60. The inner end of this screw is preferably pointed so as to insure proper centering of the same, and fits into 25 a corresponding recess formed in the inner end wall of slot 60 as shown. Screw 61 projects beyond the periphery of disk 57 and is provided with a pinion 63 secured on the outer end of the screw. This pinion is 30 adapted to be engaged by an element of a speed changing mechanism to be later described so as to cause predetermined rotation of screw 61 thus moving the block 59 toward or away from the center of disk 35 57 so as to vary the throw of crank shaft 58. I have shown eight disks or four pairs of disks which support four crank shafts 58, though it is obvious that the number of pairs of disks may be varied to suit circum- 40 stances. A connecting rod 64 has its upper end loosely secured to the central portion of crank 58, the lower end of this rod being secured to an eye 65 in a clevis 66 which is rigidly secured in the forward end of a tubular 45 lever shaft 67 which is preferably though not necessarily, of flattened elliptical cross section so as to give great strength for a minimum of weight. By rotating stub shaft 32 in the manner previously described, rotation 50 will be imparted to the pairs of disks 57 which will result in imparting vertical reciprocation to the rearward ends of the lever shafts 67. As will be noted more clearly from Figs. 18 to 21 of the drawings, 55 which illustrated the relative positions of the four sets of disks in successive order as considered from the lowermost set in Fig. 3, the pairs of disks are so relatively disposed that crank shafts 58 are spaced 90° apart. By arranging the sets of pairs of disks in this manner, I insure that there will 60 always be at least one of the lever shafts 67, the rearward or inner end of which is being raised. In Fig. 21, as will be noted, the 65 shaft 67 has been raised through half of its

upward movement whereas the shaft in Fig. 18 has reached its lowermost point and is about to start on its upward travel, the shaft in Fig. 19 being at the middle of its downward movement, and the shaft in Fig. 20, 70 being shown as raised into its highest position and starting on its downward movement. When shaft 67 shown in Fig. 21 is raised through the upper half of its upward travel, it will be followed by the shaft shown 75 in Fig. 18 which will then be followed by the shaft shown in Fig. 19 which is in turn followed by the shaft shown in Fig. 20. As will be noted, the lever shafts are raised and lowered in such a manner that the two outside shafts are followed in succession by the two inside shafts, thus insuring ease and 80 smoothness of operation.

The forward end of each shaft 67 is rigidly secured to a lug 68 which projects from 85 a disk 69 loosely mounted on the bull-wheel shaft 70 which is rotatably supported in bearing blocks 71 secured to the base flanges of side beams 1 and 2 of the main frame of the tractor. The opposite faces of disk 69, 90 are toothed so as to provide a double face gear, the teeth on one side of this gear being directed oppositely to the teeth on the other side. Disk 69 is positioned intermediate two spaced gears 72 and 73 which are secured 95 on short sleeves 74 feathered on shaft 70 so as to rotate therewith, while having limited movement toward and away from disk 69. As will be noted more clearly from Fig. 7, the sleeve 74 is of polygonal cross section 100 and the hub of the gear is centrally bored and shaped to snugly fit on this sleeve. This sleeve is also formed in two-sections so that, by removing the bull-wheel shaft from blocks 71, and removing the bull wheels 105 from the ends of the shaft, the gears may be readily removed from the shaft for cleaning, repairs, and similar purposes. The teeth of face gear 72 and the teeth on the adjacent face of disk 69 are so relatively disposed that, when shaft 67 is raised so as to cause partial rotation of disk 69 downwardly and forwardly, gears 72 will be similarly rotated so as to impart downward and forward rotation to bull-wheel shaft 70. 115 This will be clear from Fig. 4 of the drawings in which gear 72 is shown in operative position, gear 73 being shown out of engagement with the teeth on the adjacent face of disk 69. The gears 72 and 73 are forced 120 toward drive gear 69 by leaf springs 76 and 77 which are carried by annular plates 78 and 79, respectively, which are mounted loosely on shaft 70 adjacent the side beams 1 and 2 and intermediate the sleeves 74. By 125 moving gears 72 away from their respective disks 69 so as to be out of engagement therewith, and releasing gears 73 so as to permit them to be moved into engagement with the teeth on the adjacent faces of the 130

disks 69, the shaft 70 will be rotated downwardly and rearwardly during the down stroke of shaft 67, the teeth of disk 69 sliding over the teeth of gear 73 on the upward stroke, and, when gear 72 is in operative position, the teeth on the adjacent face of disk 69 will slide over the teeth of gear 72 on the downward stroke of this lever. By this means, the direction of rotation of the 10 bull wheel shaft and the direction of travel of the tractor can be readily reversed.

The lever shafts 67 are of relatively great length and the bull wheel shaft 70 provides a fulcrum about which these lever shafts 15 may rock at their forward ends. By this construction, due to the great leverage exerted by the shaft 67, it is possible to obtain relatively great power from a small initial power, rendering it possible to use an 20 internal combustion engine of standard construction while producing a tractor of very great power. By varying the distance of travel vertically, or the throw, of the levers 67 at their rearward ends, the length of the 25 arc through which the drive disks 69 are moved may be readily varied. As the speed of rotation of the gear 72 or 73, as the case may be, depends directly upon the speed of oscillation and the amplitude of movement 30 of the disk 69, this renders it possible to vary and accurately adjust the speed of rotation of shaft 70 by adjusting the throw of the lever shaft. For this purpose, I have provided means whereby the throw of these 35 shafts may be automatically and accurately adjusted as desired for the purpose set forth.

For changing the direction of rotation of the bull wheel shaft, I provide the gear changing means illustrated in Figs. 1 and 40 6 of the drawings, to which particular attention is called. A U-supporting frame 80 is secured to side beams 1 and 2 of the main frame and extends above disks 69 and gears 72 and 73. The top bar 81 of this frame is 45 in vertical alignment with the bull wheel shaft 70. A plurality of vertical shifting rods 82 are rotatably mounted through bar 81 and project downwardly between peripheral flanges 83 and 84 provided on gear 73 and disk 69, respectively. Each of these 50 rods is provided, on its lower ends, with a shifting head 85 which is disposed at right angles to the rod and forms therewith a T-member. This head is of such length, that, 55 when turned into substantial parallelism with bar 81 of frame 80, its opposite ends engage the flanges 83 and 84 so as to force gear 73 away from disk 69. An operating arm 86 is secured on the upper end of rod 50 82 above bar 81 of frame 80. The outer ends of these arms are pivotally secured to an operating rod 87 one end of which is connected by a tension coil spring 88 to bar 81 adjacent one end thereof. Shifting rods 89 60 similar to rods 82 are mounted in top bar 65

81 of frame 80 and are provided at their lower ends with shifting heads 90 disposed at right angles thereto and of such length that when turned into parallelism with bar 81, they engage the annular flanges 84 and 70 91 of disk 69 and gear 72, respectively so as to force gear 72 away from the disk against the action of the leaf spring 77 or 76. The upper ends of rods 89 are connected by arms 92 secured thereto to an operating rod 75 93 to which the outer ends of the arms are pivotally secured. One end of this rod is connected by a tension coil spring 94 to the frame 80. These coil springs 88 and 94 act to normally hold the rods 87 and 93 in such 80 position as to permit engagement of both of the gears 72 and 73 with the opposite gear faces of the double face gear or disk 69. By moving one or the other of these rods longitudinally against the tension of its spring, 85 the gears of either set of gears desired may be moved out of engagement with the drive disks 69 so as to cause the bull wheel shaft 70 to be rotated in the direction desired, as previously explained. Also, by properly adjusting both of the rods 87 and 93 both sets of gears may be held out of engagement with the drive disks, thus permitting the disks to idle on the shafts, when this may be desirable or necessary. In Fig. 5, the 90 adjusting rods 82 are shown in such position as to hold the gears 73 out of engagement with disks 69, gears 72 being in engagement with the drive disks or gears.

An operating cable 95 is secured to the 100 other end of bar 87. This cable is passed about and over suitable guide pulleys, being led rearwardly of the main frame of the tractor and secured to an arm 96 which is secured to the inner end of the shaft of a hand lever 97 rockably mounted on a segmental rack 98 secured to frame beam or base 99 of a rack and lever supporting frame indicated generally by 100 which is mounted on side beam 1 of the main frame. Hand 105 lever 97 is provided with the usual spring pressed detent indicated generally by 102 which cooperates with rack 98 to secure the lever in rocked adjustment. By rocking lever 97 downwardly and backwardly into 110 the position shown in Fig. 22, cable 95 will act to draw the rod 87 transversely of the main frame toward the side bar 1. This results in turning the shifting rods 82 into such position as to force the gears 73 out of 115 engagement with the face gears 69. This operation will be clear from Figs. 22 and 5 of the drawings. A cable 103 is secured to the other end of rod 93 and is passed about suitable guide pulleys and led rearwardly 120 of the main frame above side beam 1, thereof, the rearward end of this cable being secured to an arm 104 secured on the shaft 105 of a hand lever 106 which is rockably mounted on the segmental rack 107 carried 125 130

- by frame 100 and is provided with a spring 108 which engages the rack for the purpose of securing the lever in adjustment. By rocking lever 106 downwardly and forwardly into approximately the position shown in Fig. 23 of the drawings, cable 103 is slackened so as to permit rod 93 to be moved transversely of the same toward side beam 2 by the action of tension spring 94 thus turning the gear shifting heads 90 of the rods 89 into operative position and permitting the gears 72 to be moved into engagement with the face gears on the adjacent faces of the drive disks 69, as in Fig. 5 of the drawings. By moving both of the levers 97 and 106 downwardly and rearwardly into approximately the position in which lever 97 is illustrated in Fig. 22, both of the rods 87 and 93 will be moved into their extreme positions toward side beam 1 of the frame thus forcing both sets of gears out of engagement with the drive disk 69 so as to permit these disks to idle upon the bull wheel shaft when it becomes necessary or desirable. By means of the levers 97 and 106 and their coöperating detents, the drive gears may be readily shifted so as to rotate the bull wheel shaft in either direction desired, or so as to disconnect both sets of gears from the drive disks thus permitting these disks to idle upon the bull wheel shaft.
- A bull wheel designated generally by 110 is mounted on the shaft 70 at each end thereof. This bull wheel is provided with a hub 111 having the hub flanges 112 which are connected by the usual hooks and brace rods to tread or rim 113. The inner end of the body of hub 111 is toothed to provide a clutch element 114. This clutch element is adapted to be engaged by the teeth of a co-operating clutch member 115 which is feathered on an inner clutch member 116 feathered on shaft 70, this inner clutch member being provided with teeth at its outer end which coöperate with the teeth formed at the inner end of a reduced clutch element 117 integral with the body of hub 111 and projecting inwardly beyond clutch element 114, this reduced member 117 corresponding in exterior diameter to the interior diameter of clutch member 115. The teeth of clutch element 114 and clutch member 115 are so disposed as to operatively connect the bull wheel to the shaft when the shaft is rocked or rotated downwardly and rearwardly, clutch member 116 serving to connect the bull wheel to the shaft when it is rotated downwardly and forwardly so as to cause forward travel of the tractor. An annular plate 118 is secured to the outer face of the adjacent side beam of the main frame and is provided with two outwardly projecting diametrically opposite arms 119. Each of these arms is provided with two spaced outwardly directed pins 120 and 121. Pins 120 project through the diametrically opposite ears of a sectional band 122 which is secured about clutch member 115 and fits into an annular groove adjacent the inner end thereof. Coil expansion springs 123 are mounted about each of the pins 121 and confined between the ears of the band 122 and collars 124 secured on the pins. Springs 123 act to force clutch member 115 outwardly into engagement with clutch member 114 so as to operatively connect the shaft to the bull wheel when the shaft is rotated reversely or downwardly and rearwardly. Expansion springs 125 are mounted about the pins 120 which project through diametrically opposite ears 126 of a band 127 which is formed in two sections and secured about the clutch member 116, this band being positioned within an annular groove formed adjacent the inner end of the clutch member. These expansion springs act to force the clutch member 116 outwardly so as to hold it normally in engagement with clutch element 117 of hub 111 of the bull wheel. By this means, the bull at each end of shaft 70 may be connected directly to the shaft so as to be rotated downwardly and forwardly thereby for causing forward travel of the tractor, or they may be connected to the shaft by means of clutch member 115 through clutch members 116 so as to be rotated downwardly and rearwardly to cause rearward travel of the tractor. For this purpose suitable means are provided for moving either pair of the clutch members into or out of operative position and for securing them in inoperative position.
- Operating cables 128 and 129 (Figs. 4 and 5 and 22 to 24 inclusive,) are secured to the bands 122 and 127 of clutch members 115 and 116, respectively, adjacent side beam 2 of the main frame. These cables are passed about suitable guide pulleys and across the forward end of the main frame, and are then led rearwardly of side beam 1 above the base flange thereof and inside of the web of this beam. Cable 128 is passed upwardly over suitable guide pulleys carried by the frame 100 and through aligned openings in the web or case plate 99 of this frame and the flange of side beam 1, being then secured to the inner end of the head 130 of a T-arm 131 which is secured to the sleeve shaft 132 of a hand lever 133 which is rockably supported by a segmental rack 134 carried by frame 100, this hand lever being provided with a detent which coöperates with the rack to secure the lever in rocked adjustment. Cable 129 is passed upwardly over suitable guide pulleys carried by the frame 100 and is secured to the inner end of head 135 of a T-arm 136 which is secured to the inner end of sleeve shaft 137 of hand lever 138 rockably supported by a rack 139 carried by frame 100.

ried by frame 100 and provided with a detent coöperating with the rack to secure the lever in rocked adjustment. As will be noted more clearly from Fig. 22, the toothed 5 portion of rack 139 so that the two levers 133 and 138 have limited movement in opposite directions and at opposite sides of that vertical plane which connects the centers of these two racks, thus preventing interference 10 of operation of these two levers.

A cable 140 is secured to the band 122 of clutch member 115 adjacent the side beam 1 of the main frame and is led rearwardly along the side beam over suitable pulleys. 15 This cable is secured to the other end of head 130 of T-arm 131 carried by the sleeve shaft 132 of hand lever 133. By this means, the two clutch members 115 at the opposite sides of the main frame are connected to 20 hand lever 133 so that, by rocking this lever downwardly and rearwardly, and securing it in this position, the clutch members 115 will be secured in inoperative position out of engagement with the clutch elements 114 25 of the wheels. Band 127 of clutch member 116 adjacent side beam 1 is connected by a cable 141 to the other end of head 135 of T-arm 136 which is secured to hand lever 138. By rocking hand lever 138 upwardly and rearwardly the two cables 141 and 129 will be tensioned so as to draw the clutch members 116 inwardly out of engagement with clutch elements 117 of the bull-wheels. When lever 138 is rocked 30 downwardly and forwardly into substantially the position shown in Fig. 22, these clutch members are released so as to operatively connect the bull wheels to shaft 70 for forward and downward rotation so as to 35 cause forward movement of the tractor, as shown in Fig. 5. By means of these telescoping clutches and the lever and cable control therefor, the bull wheels may be readily connected to the bull wheel shaft so as to 40 cause rotation thereof when the shaft is rotated, or may be secured in inoperative position if desired or necessary. If desired, the telescoping clutch members may remain in their outermost or operative position, and 45 will thus form automatically acting clutches by means of which the bull wheels will be operatively connected to the bull wheel shaft when it is rotated in either direction, one set of the clutches being in engagement with 50 the corresponding elements of the hubs of the bull wheels and the other set of clutches sliding over the teeth of the other elements of the hubs of the bull wheel. However, I prefer as a general rule to secure the clutches 55 which are not in use in inoperative position so as to prevent unnecessary wear or rubbing of the clutch faces of the elements.

To enable the speed at which the tractor is operated to be varied, I provide a speed 60 changing mechanism which is illustrated in

Fig. 3, Figs. 14 to 17 inclusive, and Figs. 18 to 21 inclusive. As previously stated, each of the crank shafts 58 is supported by a pair of drive disks 57, these disks being provided with radially extending slots 60, which 70 are in alinement transversely of the tractor frame and slidably receive blocks 59 formed at the ends of the crank shaft. The adjusting screw 61 is normally locked against rotation by a spring catch 143 secured to disk 57 75 adjacent the periphery thereof and engaging into an arcuate recess in the underface of pinion 63 (Fig. 25.) This screw 61 has a thread of such a pitch that, when the screw is moved through one complete rotation, the 80 block 59, and consequently crank shaft 58, will be moved a predetermined distance, such as three-eighths of an inch, radially of the disk. By moving the blocks of the disk outwardly or away from the center of the disks, 85 the throw of the free end of lever shaft 67 will be increased thus increasing the amount of movement of the drive disk or gear 69 which results in increased rotation of the bull-wheel shaft 70 thus accomplishing an 90 increase in speed of the tractor. By moving the block 59 toward the center of the disk 57, the speed of travel of the tractor will be correspondingly decreased. A substantially rectangular frame 144 is secured 95 on the forward portion of cross beam 53^a. This frame is in alinement with disk 57 and slidably supports two rods 145 and 146, for movement toward and away from the disk. Rod 145 is provided, at its forward end, with an arcuate rack head 147 which is curved on an arc corresponding to the distance of pinion 63 from the center of disk 57. Rod 146 is provided on its inner 100 end with a similar head 148. The inner 105 faces of these two heads are toothed to provide rack surfaces for engagement with pinion 63, as indicated in Fig. 17. These two heads are so spaced as to engage the pinions at opposite sides of the axes thereof when 110 in forward position thus causing the pinion to be rotated in one direction by one head, and in the opposite direction when it engages the other head. The rack heads are, preferably of such length as to move the pinion 115 63, and consequently the adjusting screw 61, through one complete rotation for each rotation of disk 57. Rod 145 is normally forced forward by an expansion coil spring 149 mounted about the rod and confined between 120 a collar 150 secured on the rod and the inner end arm 151 of the frame 144. Rod 146 is forced forwardly in a similar manner by a coil expansion spring 152. These two rods are secured against rotary movement by pin and slot means, or in any other suitable manner so as to insure that the rack heads carried thereby will at all times be disposed in vertical position. The rearward portion of rod 146 is centrally recessed and 125 130

slotted to receive a latch 153 which is rockably mounted therein. This latch is provided with a head 154 which projects below rod 146 so as to engage the inner wall 151 of frame 144 thus securing the rod against forward movement, as in Fig. 17. The forward end of latch is normally held in raised position so as to hold the head 154 in depressed position by means of a leaf spring 155 engaging the underface of stem 156 of the latch. Rod 145 is held in retracted position by a similar latch designated generally by 157. Normally, both of the rods 145 and 146 will be held in retracted position so as to prevent engagement of pinion 63 with either of the rack heads 147 or 148 when the disk is rotated. When it is desired to alter the speed of travel of the tractor, one of the rods will be released so as to permit engagement of the rack head carried thereby by pinion 63 so as to shift the crank shaft 58 either toward or away from the center of disk 57, depending upon whether it is desired to increase or diminish the speed of travel.

In practice, I provide both of the frames 144 with corresponding rods, rack heads, latches and associated parts. Each of the frames 144 is provided, at its rearward end, with an integral rearwardly projecting block 158 having an integral finger 159 projecting rearwardly therefrom. The blocks 158 rockably support a tripping shaft 160 which extends transversely of the frame. This shaft 35 is provided with a plurality of spaced tripping cams 161 secured thereon and adapted to engage the heads 154 of the latches 153 when shaft 160 is rocked downwardly and rearwardly so as to raise the same. This 40 operation will be clear from Fig. 17 of the drawings. A similar shaft 162 is rotatably supported in the rearwardly projecting fingers 159 and is provided with tripping cams 163, for raising the latches 157 to release 45 rods 145. If it is desired to increase the speed of the tractor, rod 162 is rocked so as to release the plunger rods 145 thus permitting rack head 147 to be moved forwardly into position for engagement by the 50 pinion 63, of the disk 57. This forward movement of each of the rods 145 is positively limited by the collar 150 so as to insure that the head will be brought into position for proper engagement by the pinion, 55 as indicated in Figs. 14 and 15. As disk 57 rotates a pinion 63 will engage the rack head 147 so as to be turned through a complete rotation in a clockwise direction thus moving the blocks 59, and consequently 60 crank shaft 58, away from the center of the disk so as to increase the speed of the tractor. After the pinion has been thus rotated, it will be locked against rotation by the spring latch 143 previously referred 65 to. Disk 57 is provided, at each side, with a laterally and radially projecting lug 164. This lug acts to engage the rack head after the adjusting screw 61 has been rotated in the manner set forth and serves to return this head and the rod 145 to inoperative 70 position, in which position they are retained by the latch 157. If it is desired to decrease the speed of travel, this is accomplished by rocking rod 160 so as to release the rods 146 when pinion 63 will engage 75 rack head 148 so as to be rotated thereby in a counter-clockwise direction, thus moving the blocks 59 toward the center of the disk instead of away from it, rod 146 and rack head 148 being then returned to inoperative 80 position by the lug 164 in which position they are secured by the latch 153.

An arm 166 is secured on one end of shaft 160. A tripping lever 167 has its rearward end pivotally secured to the upper end of 85 arm 166. This lever is operable in a guide frame 168 secured to main frame beam 1 and provided with a vertical slot 169 which receives a lever, the outer bar 170 of this frame being provided within a short distance 90 from its upper end with a recess 171 contiguous to slot 169. This recess is adapted to receive a spring latch 172 secured to the inner face of bar 170 adjacent the upper end thereof. This latch is provided, at 95 its lower end, with an inwardly directed head 173, the lower face of which is inclined downwardly and outwardly. When tripping lever 167 is raised into its uppermost position, head 173 engages under this 100 lever so as to maintain it in raised position. A similar tripping lever 174 is pivotally secured at its rearward end to an arm 175 which is secured to shaft 162. Lever 174 is operable in the vertical slot 176 in guide frame 168 105 and is normally held in raised position by the spring latch 177 which corresponds to latch 172. Releasing rod 178 projects through slot 169 above tripping lever 167 and adjacent the upper end of latch 172, 110 the forward end portion of this rod being rotatably supported by the cross pieces 179 secured to the frame. Rod 178 carries a releasing cam 180 which is normally directed downwardly so as to be out of engagement with latch 172. A similar releasing rod 181 projects through the upper portion of slot 176 and is provided with a downwardly directed cam 182 for moving latch 177 into inoperative position. Rod 178 115 is secured to a hand lever 183 which is rockably supported on a standard 184 carried by the frame 100. This hand lever is positioned adjacent a segmental rack 185 and is provided with a spring pressed detent 120 which cooperates with the rack to secure the lever in rocked adjustment. Rod 181 is similarly secured to a hand lever 186 which is mounted at the opposite side of standard 184 from lever 183 and is provided 125 130

with a detent which coöperates with a rack 187 to secure the lever in adjustment. (Figs. 3, 23, 22, and 24). As will be noted, the hand levers 183 and 186 extend transversely of the frame 100 beneath the hand levers 138 and 97, being so disposed as to prevent all interference between these levers. When it is desired to increase the speed of travel of the tractor, hand lever 186 is rocked upwardly and outwardly so as to bring the cam 182 into engagement with spring latch 177 thus releasing the tripping lever 174 which will be operated in a manner to be described to rock shaft 162 in such direction as to release the rods 145. If it is desired to decrease the speed of travel, hand lever 183 is rocked downwardly and inwardly thus bringing cam 180 into engagement with spring latch 172 and forcing this latch into the recess 171 so as to release lever 167 as in Figs. 14 and 16. When lever 167 is released, it drops into such position as to rest upon the tripping cam 188 which is secured upon the outer end of stub shaft 55. This cam is provided with a shoulder 189 which is adapted to engage a coöperating shoulder 190 provided adjacent the forward end of lever 167. When the shoulder of the cam engages the shoulder of the lever the lever will be rocked or forced rearwardly a sufficient distance to rock shaft 160 downwardly and rearwardly so as to bring the tripping cams carried thereby into engagement with the heads 154 of the latches 153 thus releasing rods 146 and permitting the rack head 148 carried thereby to be moved into position for engagement with the pinions 63 so as to cause rotation of the setting screw 61 in the manner described. After shaft 160 has thus been rocked, the shoulder of the cam will pass out of engagement with the shoulder of the tripping shaft or bar which will then ride upon the rim of the cam. This bar being moved forwardly by means of a tension coil spring 193 secured thereto and to frame 168 so as to return releasing cams 161 of shaft 160 to normal or inoperative position. This cam is provided with an extended portion or nose 191 which is of such length and so relatively disposed as to engage the tripping bar 167 and raise it into inoperative position after the adjusting screw 61 has been rotated and rack head 148 has been returned to inoperative position, the tripping bar being maintained in raised or inoperative position by the spring latch 172 until again released in the manner described. If it is desired to increase the speed of travel, tripping bar 174 is released and will be actuated in the same manner as bar 167 by means of the cam 188 to release the rods 145 and rack head 147 carried thereby so as to cause rotation of screw 61 in the opposite direction, after which the rods and

rack heads will be retained in inoperative position as previously described. A tension coil spring 194 is secured to bar 174 and to frame 168 and acts to cause forward movement of this bar when released from the shoulder of cam 188 so as to return cams 165 to normal position. By this arrangement, a predetermined increase or decrease in the speed may be readily obtained. Of course, by securing either of the levers 183 or 186 in such position as to maintain the corresponding tripping bar in lowered or operative position, the speed of the tractor will be either increased or diminished a predetermined amount for each complete rotation of the disk 57. When the desired speed has been attained, the lever may be raised into such position as to cause the tripping rod to be retained in inoperative position, after which the speed which has been attained will be maintained until a further adjustment is made. By having the crank shaft 58 movable radially of disk 57, I attain a very wide range of adjustment in speed, while rendering it possible to so reduce the speed as to obtain very great power when required. Also, by this construction of the speed changing mechanism, accurate and very slight adjustment in the speed of travel of the tractor may be readily obtained. Suitable hoods or covers are provided over and about the driving and speed changing mechanisms and over the drive gearing, to prevent entry of dust, grit, and other foreign materials.

While I have illustrated and described in detail the construction of the various mechanisms, of my tractor it will be evident that there may be slight changes made in the construction and arrangement of the various parts of my invention without departing from the field and scope of the same, and I intend to include all such variations in this application as fall within the scope of the appended claims.

What I claim is:

1. In a device of the class described, the combination with a driven shaft, driving disks loosely mounted thereon and having oppositely directed teeth on opposite sides, a source of power, and connections between said source and disks for oscillating the latter; of face gears feathered on said shaft at opposite sides of the disks, springs bearing them normally toward the disks and their teeth into engagement with the teeth on the disks, means between each disk and its respective gears for moving the latter outward when desired, and manually operable mechanisms for actuating said means, for the purpose set forth.

2. In a tractor, a bull wheel shaft, drive disks loosely mounted on the shaft so as to be oscillatable thereon, the opposite faces of each disk being provided with outwardly

- directed teeth so as to provide oppositely directed face gears, face gears positioned adjacent each side of said disk and feathered on the shaft so as to be movable into and out of engagement with the face gears of the disk, means for oscillating said disk, and means for moving said face gears into and out of engagement with the face gears of the drive disk so as to cause rotation of the shaft in either direction desired when said disks are oscillated. 3. In a tractor, a bull wheel shaft, disks loosely mounted on said shaft so as to be freely oscillatable about the same, each of said disks having its opposite faces provided with outwardly directed teeth so as to provide oppositely directed face gears, face gears positioned adjacent the opposite faces of each of said disks, said face gears being feathered on the shaft, yielding means for forcing said face gears into engagement with the face gears of the disks, and means for optionally moving either of said face gears away from said disks. 4. In a tractor, a bull wheel shaft, drive disks loosely mounted on said shaft, each having oppositely directed teeth on its opposite sides, face gears mounted adjacent both sides of the disks and feathered on the shaft, means for normally forcing said face gears toward the disks, T members having their heads between said gears and disks, means for oscillating said disks, and means for operating said T-members optionally so as to force either of the face gears away from the disks. 5. In a tractor, a bull wheel shaft, drive disks loosely mounted on said shaft so as to be oscillatable about the same, each of said disks being provided with oppositely directed teeth on its opposite sides so as to provide oppositely directed face gears, face gears mounted adjacent each side of the drive disks and feathered on the shaft so as to be movable into and out of engagement with the face gears of said disks, means for normally forcing said face gears toward the disks so as to be in engagement therewith, the face gears and the disks being provided with outwardly projecting annular flanges, T-members mounted about said gears and disks and having their heads positioned intermediate the flanges thereof and of such length that when directed in parallelism with the axis of said shaft, they will engage the flanges of the disks and face gears so as to force the face gears out of engagement with the disks, means for oscillating said disks, and means for operating said T-members so as to force either of the face gears on the shaft away from the disks so as to cause rotation of the shaft in either direction desired when said disks are oscillated. 6. In a tractor, a frame, a bull wheel shaft rotatably supported thereby, a lever fulcrumed at its forward end for oscillatory movement, a pair of driving disks rotatably supported by the frame and provided with axially extending aligned slots, blocks slidable in said slots, a shaft carried by said blocks, connections between said shaft and the rearward end of the lever so as to cause oscillatory movement of the lever when the disks are rotated, adjusting screws threaded through said blocks and secured against axial movement for adjusting the blocks radially of the disks so as to vary the amplitude of oscillation of the lever, pinions secured on said screw, and rack heads movable into and out of position for engagement by said pinions when the disks are rotated so as to cause predetermined rotary movement of the screws for adjusting said blocks a predetermined distance radially of the disks. 7. In a tractor, a frame, a shaft rotatably supported thereby, a lever fulcrumed at its forward end for oscillatory movement, means for establishing driving connections between said lever and shaft for causing rotation of the shaft when the lever is oscillated, a pair of driving disks rotatably supported by the frame, said disks being provided with radial aligned slots, a shaft mounted between said disks and provided at its ends with blocks slidable in the slots of the disks, adjusting screws threaded through said blocks and secured against axial movement for adjusting the blocks radially of the disks when the screws are rotated, adjusting pinions secured on said screws, rack heads movable into and out of position for engagement by said pinions when the disks are rotated, means for releasably securing said rack heads in inoperative position, means for moving the rack heads into operative position when released, and means for returning the rack heads to inoperative position after engagement of the same by the pinions. 8. In a tractor, a frame, a shaft rotatably supported thereby, a lever fulcrumed at its forward end for oscillatory movement, means for establishing driving connections between said lever and shaft for causing rotation of the shaft when the lever is oscillated, a pair of driving disks rotatably supported by the frame, said disks being provided with radially aligned slots, a shaft mounted between said disks and provided at its ends with blocks slidable in the slots of the disks, adjusting screws threaded through said blocks and secured against axial movement for adjusting the blocks radially of the disks when the screws are rotated, adjusting pinions secured on said screws, rack heads movable into and out of position for engagement by said pinions when the disks are rotated, means for re-

leasably securing said rack heads in inoperative position, means for moving the rack heads into operative position when released, and means carried by the disks and engageable with the rack heads for returning the same in inoperative position.

9. In a tractor, a frame, a shaft rotatably supported thereby, an operating lever fulcrumed at its forward end for oscillatory movement, means for establishing driving connections between said lever and shaft for causing rotation of the shaft when the lever is oscillated, spaced axially alined driving disks rotatably supported by the frame and provided with radially extending alined slots, a shaft mounted between said disks and provided at its ends with blocks slideable in the disks, connections between said shaft and the rearward end of the operating lever for causing oscillatory movement of the lever when the disks are rotated, adjusting screws threaded through said blocks and secured against longitudinal movement for adjusting the blocks radially of the disks when said screws are rotated, means for normally securing the adjusting screws against rotation, pinions on the screws, and racks movable into engagement with the pinions for optionally causing predetermined rotation of the adjusting screws in either direction so as to adjust the blocks radially of the disks.

10. In a tractor, a frame, a shaft rotatably supported thereby, an operating lever fulcrumed at its forward end for oscillatory movement, means for establishing driving connections between said shaft and lever for causing rotation of the shaft when the lever is oscillated about its fulcrum, a pair of driving disks rotatably mounted in said frame in axial alinement and provided with radially extending alined slots, a shaft provided at its ends with blocks slideable in the slots of said disks, connections between said shaft and the rearward end of the operating lever for causing oscillatory movement of the lever when the disks are rotated, adjusting screws threaded through said blocks and secured against axial movement for adjusting the blocks radially of the disks, pinions secured on said screws and of greater diameter than the thickness of the disks, pairs of rack heads positioned adjacent the disks and movable into and out of position for engagement by the said pinions, the rack heads of each pair being independently movable and being spaced apart the diameter of the corresponding pinion so as to engage the pinion at either side of its axis when in operative position and cause rotation of the adjusting screw in either direction desired, means for moving the rack head into operative position when released, and means for returning said rack head to inoperative posi-

tion after engagement therewith by said pinion.

11. In a tractor, a frame, a bull wheel shaft rotatably supported thereby, an operating lever fulcrumed at its forward end for oscillatory movement, means for establishing driving connections between said lever and the bull wheel shaft for causing rotation of the shaft when the lever is oscillated, a pair of axially alined spaced driving disks rotatably supported by the frame, said disks being provided with radially alined slots, a shaft provided at its ends with blocks slideable in said slots, adjusting screws threaded through said blocks and secured against axial movement for adjusting the blocks radially of the disks when the screws are rotated, adjusting pinions secured on the outer ends of said screws beyond the periphery of the disks, rack heads movable into position for engagement by said pinions when the disks are rotated so as to cause predetermined rotary movement of the adjusting screws, means for securing said rack heads in inoperative position, means operable by the disks for releasing the rack heads when the disks have reached a predetermined rotary position so as to cause the pinions to engage said rack heads, means for returning the rack heads to inoperative position after engagement thereby with the pinions, and means for returning said releasing means to inoperative position.

12. In a tractor, a frame, a bull wheel shaft rotatably supported thereby, an operating lever fulcrumed at its forward end for oscillatory movement, means for establishing driving connections between said lever and the shaft for causing rotation of said shaft when the lever is oscillated at its fulcrum, a pair of driving disks rotatably supported by the frame and provided with radially extending alined slots, a shaft mounted between said disks and provided at its ends with blocks slideable in the slots, adjusting screws threaded through said blocks and secured against axial movement, pinions secured on said screws beyond the peripheries of the disks, supporting frames mounted in alinement with said disks, rods slideable in said frame toward and away from the disks and provided on their forward ends with rack heads spaced apart the same distance as the diameter of the pinions, said heads being movable into and out of position for engagement by the pinions when the disks are rotated, means for normally forcing the rods carrying the rack heads toward the disks, releasable latches carried by said rods acting to normally secure the same in retracted position, a tripping shaft rockably supported by said supporting frame and provided with tripping cams movable into engagement with said

- latches for releasing the rods when the shaft is rocked, a tripping rod secured to said shaft so as to cause rocking thereof so as to release the rods carrying the rack heads 5 when said tripping rod is moved rearwardly of the tractor frame, means for releasably holding said tripping rod in raised position, and a tripping cam secured on the shaft of one of the disks and provided with a shoulder 10 adapted to engage a corresponding shoulder on the tripping rod when the disks are rotated and the tripping rod is in lowered position, said cam being adapted to return the tripping rod to inoperative position as rotation of the disks continues, means 15 for returning said tripping shaft to inoperative position immediately after engagement of the tripping rod by the shoulder of the cam, and a projecting lug carried by each of said disks for engagement with the 20 said rack heads for returning the same to inoperative position immediately subsequent to engagement of said heads by the pinions of the adjusting screws.

In testimony whereof I affix my signature 25 in presence of two witnesses.

WILLIAM A. PETERSON.
